TAPERED PILING

Gerald G. Greulich, Mount Lebanon, Pa.

Application December 29, 1937, Serial No. 182,355

1 Claim. (Cl. 61—53)

The present invention relates to metallic piling and, more particularly, to a metallic shell for casting concrete piles.

An object of the present invention is to provide a tapered metallic piling shell with integral projecting stiffening ribs increasing in width as the diameter of the pile section decreases.

A further object is to provide a tapered pile possessing sufficient strength to withstand the impact forces imparted thereto during the driving of the pile into position.

Other objects and advantages will become apparent as the description proceeds, in which:

Figure 1 is a sectional elevation of the present invention;

Figure 2 is a top plan of the showing in Figure 1;

Figure 3 is a top plan of a piling shell including four complementary sections;

Figure 4 is a top plan showing how the piling shell can be made from two complementary semi-cylindrical sections;

Figure 5 is a modified form of tapered piling shell in which the shell is made up of a plurality of relatively short lengths welded together;

Figure 6 is a top plan of Figure 5 showing the reinforcing ribs; and

Figure 7 is a modified form of the manner of welding the segmental sections together.

In the drawing, the numeral 2 designates the preformed complementary metallic sections forming the piling shell. These complementary sections may be made of rectangular stock and preformed to the desired cross-sectional shape with flanges 3 extending laterally from said sections.

The flanges 3 increase in width as the conical portion of the pile decreases due to the taper produced during the forming operation, which may be any standard practice, for example, a press having interchangeable dies so that a uniform degree of taper may be produced in the complementary sections forming the assembled piling shell. These flanges provide reinforcing ribs throughout the longitudinal length of said

piling shell and, due to their increasing width, sufficient rigidity is supplied to said pile during the driving operation to permit the piling shell to resist lateral forces which might tend to force the shell out of its line of travel through the ground strata. However, if desired, the complementary sections may be so formed as to eliminate the lateral flanges and, under such a construction the edges of the complementary sections may be overlapped and welded, in any conventional manner, as shown in Figure 7.

The piling shell may be made up from a number of preformed like segmental sections, as shown in Figures 2 through 4, which, when welded at their respective flanges, will provide a unitary complementary section adapted to abut another preformed section and be welded at their abutting edges.

The piling shell may be produced as shown in Figure 5 by providing preformed standardized lengths of sections 5, 6, 7, 8, 9 and 10 of varying diameters and degrees of taper so that when each preformed section is positioned and arranged for welding to the next section, there is produced a unitary piling shell of desired length and taper. Under this form of construction, each segmental section is provided with longitudinally disposed reinforcing ribs 12 which, together with the welded flanges 14, provide sufficient reinforcement for the light gage stock to withstand the force transmitted to said piling shell during the driving operation.

Secured to the penetrating end of the assembled shell, by welding or otherwise, is a piercing point 15 having an annular flange 16 extending within and engaging the inner wall 25 of the unitary section 2.

The piling shell of the present invention is preferably formed from relatively light gage stock, and it is therefore necessary that the end be protected during the driving operation to 30 position the shell in the ground prior to the pouring of concrete. A protective ring 17 is positioned within the driving end of said piling shell, said ring having a flange 18 extending outwardly to a point substantially coincident with the outer 35 edges of the flanges 3.

The number of segmental units desired to form the piling shell are positioned in superimposed relationship and welded into a unitary assembly so as to produce, in one case, a tapered piling shell having flanges or ribs increasing in width 40 as the diameter of said piling shell decreases and, in another case, a plurality of preformed sections of varying diameter and degrees of taper which, when welded together, produce a unitary tapered 45 structure having ribs of uniform width throughout the tapered assembly.

Instead of providing the segmental sections with uniform or increasing width flanges, these segmental sections may, if desired, have their 50 edges overlapped and welded, as shown in Figure 7.

While I have shown and described specific embodiments of the present invention, it will be understood that I do not wish to be limited ex-

acty thereto, since various modifications may be made without departing from the scope of the invention, as defined by the following claim.

I claim:

- 5 A tubular metallic pile shell comprising a plurality of complementary arcuate sections welded together to provide a hollow chamber whose interior diameter gradually decreases toward its bottom portion, a piercing point welded to the bottom portion of said hollow chamber, integral reenforcing ribs on said arcuate sections increasing in width as the diameter of the piling shell
- 10

decreases, the outer extremities of said reenforcing ribs being parallel to the longitudinal axis of said piling shell and a protective driving ring welded to the upper portion of said piling shell and positioned within the bore of the hollow chamber and including a laterally extending flange terminating in substantial alignment with the outer edges of said reenforcing ribs whereby said piling shell will resist lateral forces during driving of said shell to position.
